REGULATING DEVICE

Joseph F. Mustee, Cleveland, Ohio

Application July 25, 1939, Serial No. 286,391

9 Claims. (Cl. 236—21)

My invention relates to snap action levers and more particularly to snap action levers adapted to regulate the flow of gas to a hot water heater.

An object of my invention is to provide a snap action valve for regulating the flow of gas to a main burner and a pilot burner in accordance with the demands of two thermostats; one of the thermostats being governed by the existence of a pilot flame and the other of the thermostats being governed by the heat generated by the main burner.

Another object of my invention is to provide a single snap action lever which may be governed by two thermostats.

Still another object of my invention is to automatically govern the heating of a hot water tank by shutting the gas supply off and turning it on and to provide a pilot light to ignite the gas as it is turned on.

A still further object of my invention is to provide a valve which will shut the supply of gas to the pilot off when the pilot light is extinguished.

A further object of my invention is to provide a gas supply control which is normally biased open and to provide two thermostats which can independently influence the control to quickly shut the supply of gas off.

Still another object of my invention is to provide a double thermostat control for a gas supply valve and to arrange the control in such a manner that the closed valve cannot be automatically opened unless the pilot flame is ignited.

Another object of my invention is to provide a spring biased snap action lever for operating a valve and to pivotally mount the lever on two knife edges and to provide thermostatic means for moving these knife edges to cause the biasing spring to snap the lever back and forth to actuate the valve.

Another object of my invention is to provide a snap action mechanism influenced by three movable conditions.

Other objects and a fuller understanding of my invention may be had by referring to the following description and claims, taken in combination with the accompanying drawings in which:

Figure 1 of my drawing is a view of a system installation embodying my invention in which the hot water heater and storage tank are shown partly cut away and in which my invention is shown mounted on the hot water tank. Part of the casing around my invention is removed to facilitate the understanding of the invention.

Figure 2 is a sectional side view of my inven-

tion removed from the hot water tank and taken along line 2—2 of Figure 1.

Figures 3, 4, 5, and 6 are diagrammatic sketches showing the relative positions of important points of my invention through several operations.

Figure 7 is an isometric view of the snap action lever which actuates the valve in my invention, and

Figure 8 is an isometric view of another embodiment of my invention showing a snap action lever which moves on knife edges only.

For illustrative purposes I have shown my devices as used in connection with a domestic hot water heating system which utilizes a storage tank and a heater. It is to be remembered, however, that this illustration is only by way of example and that my device is adapted to many other uses.

In the preferred embodiment illustrated in Figure 1 I show the lower portion of a hot water storage tank indicated by the reference character 10, a small hot water heater 11 and my control device indicated generally by the numeral 12 and enclosed in a casing 19. In actual practice my device 12 is quite small compared to the tank and heater. However I have drawn the device 12 to an enlarged scale in order to more efficiently and accurately illustrate the various features. My device 12 is attached to the hot water tank 11 by any suitable means such as a water tight screw means 13 through the wall 14 of the tank and a bolt 15 through a flange on the device 12 and through a flange on the tank 11. Through the tank wall 14 at the water tight seal 13 I pass a thermostatic element 16 which is comprised of a highly expandable hollow tube 17 within which there is a small wire 18 of relatively non-expandable material. The wire 18 is fixed by solder or other suitable means to the bottom of the tube 17 and extends the length of the tube into my device 12.

At one end of my device 12 a gas inlet pipe 20 passes through the casing by suitable gas tight means into a chamber 21. From the chamber 21 the gas is at all times free to pass to a compartment 22 and when a valve 25 is open the gas is free to pass into a compartment 26 where the regulating mechanism of my invention is located. From the compartment 26 the gas flows into a gas pipe 27 which leads to the hot water heater 11 where it burns in a burner 28. Water is heated in the coiled pipe 29 and passes out of the heater 11 and into the storage tank 10 by means of a pipe 30.

The flame in the burner 28 is extinguished when

the water in the storage tank heats the thermostat 16 to a set degree thereby actuating my device 12 to close the valve 25 and shut off the gas supply to the burner. To relight the burner 28 when the water in the tank cools, I provide for the thermostat 16 to actuate my device 12 to open valve 25 thereby reestablishing a gas supply to burner 28, and for a pilot burner 31 to ignite the gas. Gas is supplied to the pilot burner 31 from the gas inlet pipe 20 through the compartment 21, a valve opening 33, a compartment 34, and a pilot supply pipe 35.

The burner valve 25, which in Figure 1 is shown closed, is normally biased open by a lever 36 which is actuated by a spring 37.

In operation the pilot burner 31 and the main burner 28 are ignited. The water in the coiled pipe 29 is heated and rises through pipe 30 to the top of the storage tank 10. When sufficient water has been heated the hollow thermostat tube 17 expands and pulls on the relatively non-expandable wire 18. The wire 18 is fastened to a transverse bar 38 which is in turn mounted on one side of a rotatable axis 39. The pull that is exerted on the transverse bar 38 causes the axis 39 to rotate thereby snapping the lever 36 to downward position which allows the coiled spring 40 to force the valve 25 to seat and shut off the gas supply to the main burner. The operation of the snap will be explained later. The closing of the valve 25 does not affect the pilot burner 31 as its supply is free to pass from the chamber 21 into successive compartments 22 and 34 and through the supply pipe 35 to the pilot burner.

When the supply of hot water in the storage tank 10 has been used to an extent that the cold water which replaces the used hot water affects the thermostat 16 it causes the hollow tube 17 to contract thereby relieving the tension on the wire 18. The spring actuated lever 36 by reason of its bias, will then return to its normal position thereby opening the valve 25. The restored flow of gas to the burner 28 will be ignited by the flame from the pilot burner 31 which is located close by. This cycle will continue as long as the pilot flame does not blow out while the main burner is shut off. If the pilot flame is extinguished while the main burner is ignited the pilot flame will be relighted without any thermostatic action.

To guard against having the pilot flame go out while the main burner is shut off and to prevent the thermostat 16 from opening the main burner valve 25 while the pilot is not ignited, I provide a second thermostatic action which is actuated by the heat of the pilot flame. Between the pilot burner 31 and the main burner 28 I have mounted a bimetal pilot thermostat element 42. This pilot thermostat 42 is placed between the pilot flame and the main burner in order that the flame from the pilot will strike the thermostat element before it passes to the main burner. This serves to continually keep the element hot and bent toward the main burner.

The pilot thermostat 42 is connected to the device 12 by means of a flexible control cable 43 which is carried in a bendable tube 44. An adjustment comprised of two threaded nuts 45 and double ended adjusting member 46 is inserted in the control between the thermostat element and the device 12. The nuts 45 are attached to the bendable tube in such a manner that the rotation of the adjusting member 46 will alter the position of the flexible cable 43. One end

of the control cable 43 is attached to a movable part of the thermostatic element 42 while the other end is fixed to a pivotal arm 47 in the device 12. A pilot valve 32 is attached to the flexible cable 43 and is adapted to seat in the pilot valve opening 33 when the flexible cable is actuated upon the extinguishment of the pilot flame. The seating of the pilot valve 32 shuts off the supply of gas to the pilot burner. To provide power for actuating the flexible cable 43 I insert a spring 50 in the flexible cable 43 which pulls against the bimetallic element 42. The force exerted by the bimetallic element when heated by the pilot flame 31 is opposite to and greater than the force exerted by the spring 50 and therefore prevents the pilot valve 32 from seating in the valve opening 33 as long as the pilot flame is burning. However, if the pilot flame goes out and is not immediately reignited by the flame in the main burner the bimetallic element 42 bends toward the spring 50 thereby allowing the spring to close the pilot valve 32 and cut off the flow of gas to the pilot burner. The same action by the spring 50 actuates the pivotal arm 47 and causes the main burner valve to snap shut thereby cutting off the flow of gas to the main burner. This action will be explained in detail later. To relight the pilot burner and the main burner it is necessary for a person to push in on the push button 51 which normally is held out by the spring 52. This action opens a valve 53 and permits gas to flow to the pilot burner 31. The gas at the pilot burner is then ignited. The push button 50 must be held down until the bimetallic element 42 bends sufficiently to overcome the force of the spring 50 and open the valve opening 33. The push button 50 can then be released and the spring 51 will operate to close the push button valve 53. The system is now in normal operation and will cycle of its own accord.

My device 12 by which snap action opening and closing of the main burner valve 25 is obtained is comprised of the rotatable member 39 to which the transverse bar 38 is welded or otherwise rigidly attached. The member 39 is incapable of translatory movement and is therefore a reference point for movable points on the device. To the transverse bar the non-expandable wire 18 is attached. The wire 18 is attached to the transverse bar 38 at a distance from the rotatable member 39 so that a pull on the wire 18 causes the rotatable member 39 to turn in a counter clockwise direction. Also attached to the rotatable member 39 by means of welding is a second transverse or knife edge bar 54. Rotation of the rotatable member 39 causes the knife edge bar 54 to rotate also. One end of the knife edge bar 54 turns downward substantially 90° and is provided with a first notch 55 which is adapted to receive a first knife edge bearing 56. A second notch 57 is provided into which a second knife edge bearing 58 is adapted to fit. The knife edge bearings 56 and 58 are the end points of the aforementioned substantially U-shaped lever 36 which is biased toward the valve 25 and which is held in place against the notches 55 and 57 by the action of the spring 37. One end of the spring 37 is attached to the knife edge transverse bar 54 on the opposite side of the rotatable member 39 from the first notch 55. The other end of the spring 37 is attached to the cross-bar 59 of the substantially U-shaped lever 36. The spring 37 thereby urges the lever 36 toward the transverse knife edge bar 54 there-

by holding the first knife edge bearing 56 in the first notch 55, and the second knife edge bearing 58 in the second notch 57. Ears 60 may be put on the knife edge bearings 56 and 58 to keep the U-shaped lever 36 from slipping sideways off the notches 55 and 57. A projector 61 may be attached to the cross-bar 59 to contact the valve 25 as the lever 36 snaps back and forth.

The rotatable member 39 to which the transverse bar 38 and the knife edge transverse bar 54 are attached and to which the lever 36 is spring biased, is attached to a plate 64 by means of three turned lips 65, 66 and 67. The rotatable member is set at an angle to the plate 64 and the lips which hold it there are the high lip 65 through which the rotatable member extends, the medium lip 66 through which the member extends, and the low lip 67 against which the rotatable member is journaled by a needle bearing 68. It may be said, therefore, that the first notch 55 is indirectly attached to the plate 64 but adjustable with respect thereto by the rotational movement caused by the rotation of the member 39. The second notch 57 is indirectly attached to the plate 64 by means of an L shaped member 69 which is loosely attached to the plate 64 at points 70 and 71. At the junction of the two legs the L shaped member 69 is movable with respect to the plate 64. Attached to the L shaped member 69 at the junction of its two legs is an upstanding member 62 which has thereon the second notch 57. The pivotal arm 47 is interposed between the plate 64 and the L shaped member 69 and is pivoted at point 71. Carried by the pivotal arm 47 is a positioning lug 72 having a flat top portion 73 and an inclined face portion 74. The inclined face portion 74 is adapted to engage a projection 75 which extends out from the upstanding member 62. The pivotal arm 47 is adapted to be actuated by pilot thermostat 42 and the spring 50 to swing the arm 47 thereby causing the inclined face 74 of the positioning lug 72 to move underneath the projection 75 which extends from the upstanding member 62. This action which arises when the pilot flame goes out thereby allowing the force of the spring 50 to overbalance the force of the bimetallic element 42 causes the upstanding member 62 and the second notch 57, together with the L shaped member 69, to "ride up" onto the flat top of the positioning lug 72. The elevational movement to which the second notch 57 is subjected causes the second knife edge bearing 58 to be elevated also and results in a snap-action of the lever 36. This action to which the lever 36 is subjected renders it inoperative, upon actuation by the hot water storage tank thermostat 16, to open the valve and allow gas to flow to the main burner while the pilot burner flame is out. Upon the pilot burner being reignited by the manual process heretofore described, the force of the bimetallic element 42 overpowers the force of the spring 50 and actuates the pivotal arm 47 to allow the L shaped member, the upstanding member 62, the second notch 57 and the second knife edge bearing 58 to drop back into their previous positions. Upon being repositioned the lever 36 can be actuated by the tank thermostatic element 16 to open and close valve 25. The connection from the bimetallic element 42 to the device 12 has been described as a flexible cable 43. However, from the adjusting nut 45 to the pivotal arm 47 it is desirable that the connection be stiff. To that end, therefore, I have arranged the valve 32 and a spring stop 80 be mounted on a stiff member 81.

In the above described manner I cause both the pilot burner thermostat element 42 and the storage tank thermostat 16 to actuate a single lever 36 which in turn controls the valve 25 which admits gas to the main burner. While the pilot burner is lit the lever 36 is controlled exclusively by the storage tank thermostat 16 but immediately upon a dangerous condition being instituted by the extinguishment of the flames at the pilot burner and the main burner then the pilot burner, through the same lever 36, positively prevents the main burner valve 25 from being opened by the action of the storage tank thermostat 16. The action of the flexible cable 43 and the stiff control member 81 also serves to prevent the flow of gas to the pilot burner 31 when there is no flame present to consume it, by causing valve 32 to seat and shut off the flow of gas through the opening 33.

In Figures 3, 4, 5 and 6 I have diagrammatically illustrated the changes which take place in the alignment of the first and second knife edge bearings 55 and 58, the axis of rotation of the member 39 and a point 83 where the spring 37 is attached to the knife edge transverse bar 54. These points are illustrated as an end view of Figure 2 looking from the right hand side.

My device 12 is normally biased by spring 37 to hold valve 25 open against the push of the spring 40 and normally allows gas to flow to the pilot burner 31. This position is diagrammatically illustrated by Figure 3 in which the second knife edge bearing 58 is positioned down on a base line to indicate that the pilot valve is open and burning normally. The rotatable member 39 is positioned higher than point 58. A line 84 is drawn between the two points 58 and 39. As both point 58 and point 39 are stationary with respect to the base plate 64 during normal cycling operation governed only by the storage tank thermostat 16, the line 84 is stationary. Both of the points 83 and 56 revolve about point 39 in a counterclockwise direction as the water in the storage tank 10 heats up and rotate in a clockwise direction when the hot water tank cools down. The line 85, therefore, revolves in a counterclockwise direction when the storage tank 10 heats up and in a clockwise direction when the tank cools down. When the line 85 coincides with line 84 the lever 36, which is suspended upon points 56 and 53, is in a neutral or critical position. The slightest amount of movement by line 85 causes the spring 37 to snap the lever 36 in the direction of that slight movement. Therefore, when point 83 is above line 84 the spring 37 is urging the lever upward to its fullest extent and the valve 25 is held open. When the thermostat 16 begins to heat and expand it pulls on the transverse bar 38 thereby rotating member 39 and the line 85 between points 56 and 83 in a counterclockwise direction. When the line 85 cuts through line 84 the lever 36 has passed its critical point and the spring 37 acts to snap the lever downward thereby allowing the coiled spring 40 to snap the valve 25 shut. This position is illustrated in Figure 4.

Figures 5 and 6 illustrate the action of the pilot thermostat on the device 12. In Figure 5 the following condition is illustrated: point 53 is on its base line showing that the pilot burner flame 31 is ignited; point 83 is below line 84 showing that the storage tank is full of hot water and the main burner valve closed and the flame out. Now let us suppose that the pilot burner flame is ac-

cidentally blown out. The following events now transpire: due to absence of heat the bimetal thermostat 42 actuates the pivotal arm 47 thereby causing the point 58 to move upward as indicated by the arrow in Figure 5; due to the lack of heat the storage tank 10 cools actuating the thermostat to cause the point 83 to pass through the line 84 as may be seen in Figure 6. This action would normally actuate the lever 36 to cause the valve 25 to open thereby allowing gas to flow from the unlighted main burner 28. However, due to the action of the pilot thermostat the critical line 84 has been raised and a new critical line 86 established. The point 83 has therefore failed to pass through the critical line which would open the valve 25 and accordingly the valve remains closed.

Figure 8 is another embodiment of my invention showing the plate 64 upon which the mechanism is mounted. The pilot thermostat actuating means is not shown in this view, however, it is to be understood that the means may be added. In this embodiment of my invention I use a knife edge rotatable axis 87 instead of the bearinged rotatable axis 39. This reduces friction in the device. The knife edge rotatable axis 87 is suspended by notched legs at 88 and 89 and the action is similar to the action of the bearinged rotatable axis 39.

To provide an adjustment for my device I have arranged for a turnable knob 90 to be mounted on and project through the device casing 19. A long tapered shaft 91 is attached to the knob. An upturned lip 92 is provided in the base plate 64 and the tapered shaft 91 is adapted to thrust between the base plate 64 and the casing of the device at the point where the lip 92 is turned. This action will raise or lower the plate with respect to the casing thereby adjusting the point at which the lever 36 snaps back and forth.

Although I have described my invention with a certain degree of particularity, it is understood that the present disclosure has been made only by way of example and that numerous changes in the details of construction and the combination and arrangement of parts may be resorted to without departing from the spirit and the scope of the invention as hereinafter claimed.

I claim as my invention:

1. A thermostatic control device comprising, in combination, a valve, snap action means for actuating said valve, said snap action means comprising a pivotal member, a transverse bar attached across said pivotal member and having a knife edge at one end thereof, a second knife edge, a substantially U-shaped lever to actuate the valve, a spring attached to said U-shaped lever and to said transverse bar on the other side of the pivotal member from the said knife edge and biasing the ends of the U-shaped lever to the two knife edges, first thermostatic means for actuating the transverse bar for effecting snap-movement of said substantially U-shaped lever and said valve, and a second thermostatic means for operating the second knife edge for altering the effect that the first thermostatic means has upon the snap-action movement of the substantially U-shaped lever.

2. A thermostat control device comprising, in combination, a valve member movable in two directions, snap action means for actuating said valve, said snap action means comprising a spring, a pivotal member, a bar attached transversely across said pivotal member and having

10 a first knife edge at one end and means at the other end for attaching one end of said spring, a second knife edge on the other side of said pivotal member from said first knife edge and a substantially U-shaped lever attached to the other end of the spring and biased by the spring against the first and second knife edges, said second knife edge and said pivotal member forming a plane and said first knife edge and the point on the transverse bar at which the spring attaches forming a line which is rotatable about said pivotal member and through said plane, the point at which the line coincides with the plane being a critical point above or below which 15 the said spring snaps the lever to open said valve or to allow it to close, first thermostatic means for rotating said pivotal member to effect opening and closing of said valve, and second thermostatic means for altering the location of the said plane to prevent the said line from passing through the said plane thereby rendering said snap action means inoperative when said valve is in its closed position.

3. A thermostatic control device comprising, in combination, valve means, a lever mechanism for operating said valve means including two spaced bearings and a spring biased snap action lever having two pivoted ends pivoted in the bearings and swingable about said bearings in 20 two opposite directions, first thermostatic means for moving one of said pivoted ends to cause snap action in said two opposite directions and second thermostatic means for moving the other of said pivoted ends to cause snap action in said two opposite directions independently of said first thermostatic means.

4. A thermostatic control device for controlling the flow of gas to a main burner and to a pilot burner comprising, in combination, first 25 valve means, a single lever mechanism for operating said first valve means including a spring biased snap action lever having two pivoted ends, said lever being movable in two opposite directions to control the opening and closing of said valve means and said two pivoted ends being movable, first thermostatic means for moving one of said pivoted ends to cause said lever to move with a snap action to control the flow of gas through said first valve, a second valve, and 30 a second thermostat means for moving the other of said pivoted ends to cause said lever to move with a snap action to control the flow of gas through said first valve, said second thermostat also actuating said second valve to control the flow of gas therethrough.

5. A thermostatic control device for regulating a first burner and a second burner comprising a casing having first, second and third compartments, an inlet pipe, a first valve into said 35 third compartment from said inlet pipe, snap action means for controlling said first valve, first thermostatic means for controlling the said first valve in accordance with variations in temperature caused by said first burner, second thermostatic means for controlling said first valve in accordance with variations in temperature caused by said second burner, said second thermostatic means including control means extending from said second burner through said first and second compartments to said third compartment, inlet means from said inlet pipe to said second compartment, inlet means from said second compartment to said first compartment, second valve means associated with said control means for closing the inlet means between said

second and said first compartments at the same time the snap action means closes the valve between the inlet pipe and the third compartment under the action of the second thermostat.

6. A thermostat control device comprising, in combination, a valve, snap action means for operating said valve, said snap action means including a movable point and a reference point and an adjustable point, said reference point and said adjustable point defining a critical line, first thermostatic means for controlling said movable point to cause it to pass said critical line thereby causing said snap action means to snap, and second thermostatic means for adjusting said adjustable point to alter the position of said critical line to change the location at which said movable point will pass the critical line.

7. A thermostat control device comprising, in combination, a valve, a snap action lever for operating said valve, a rotatable member mounted on knife edges and having a knife edge connection with said lever, thermostatic means for rotating said lever about said member to cause said lever to snap and means having a knife edge connection with said lever to alter the snapping of said lever as said lever rotates about said member.

8. A thermostatic control device for use with a heating burner and a pilot burner, a first valve for controlling the flow of fuel to said heating burner, a snap action lever means for operating said valve, said lever means having a first and a second end portion spaced from each other, a first bearing for said first end portion, a second bearing for said second end portion, resilient means attached to said lever means to urge it toward said bearings, the snap-movement of said

lever means being effected by shifting the relationship between the first bearing and the resilient means, a first thermostat responsive to temperature caused by said heating burner to shift said relationship for effecting snap-movement of said lever means for operating the valve in accordance with temperature variations, and a second thermostat responsive to pilot temperatures to move said second bearing to prevent the said shifting by the first thermostat from effecting snap-movement of said lever means and to hold the said valve closed upon extinguishment of the flames at said heating burner and said pilot burner, a second valve for regulating the flow of gas to the pilot burner, said second thermostat also actuating said second valve.

9. A thermostatic control device comprising, in combination, a valve, a substantially U-shaped lever having two ends for operating the valve, a first bearing for said first end, a second bearing for said second end, resilient means having two ends, means for connecting one of said ends of the resilient means to the U-shaped lever, thermostat actuating means engaging the other of said ends of the resilient means to operate the U-shaped lever with a snap-action about the two bearings, one of said bearings being movable out of alignment with the other with respect to a plane in which may be at a given instant the other bearing point and the two ends of the resilient means, and means to move said one of said bearings out of said alignment to modify the action of the resilient means on the U-shaped lever.

JOSEPH F. MUSTEE.
